Claims priority, application Germany Nov. 11, 1959

8 Claims. (Cl. 182—212)

The present invention relates to ladders.

More particularly, the present invention relates to extension ladders of the type used, for example, in fire fighting.

Conventional extension ladders of this type maintain the several ladder sections at selected elevations with respect to each other by means of hooks carried by the lower one of a pair of adjacent ladder sections and extending around a selected rung of the upper one of the pair of sections, which is to say that section which extends upwardly beyond but still overlaps the next lower section. While such hooks reliably hold the several ladder sections at the desired elevations, nevertheless they suffer from a serious disadvantage. Thus, with these conventional structures in order to collapse the extension ladder it is necessary first to expand the latter beyond the position in which it happens to be so as to separate the hooks from the rungs and enable the hooks to be turned to positions where they will not interfere with the downward movement of all except the lowermost ladder section. Thus, whenever a fireman, for example, wishes to collapse the extension ladder it is first necessary to move all except the lowermost ladder section upwardly to a more extended position through a distance approximately equal to one-half the distance between a pair of successive ladder rungs, and only after this initial extending of the ladder can it be collapsed. As a result of this requirement of first further extending the ladder before it can be collapsed, considerable skill is required to operate the extension ladder and only the most skilled firemen can operate extension ladders rapidly and efficiently.

It is therefore a primary object of the present invention to provide an extension ladder which can be moved from an extended to a collapsed position without first requiring the ladder to be extended beyond the extended position it happens to be in before it is desired to collapse the ladder.

Another object of the present invention is to provide a structure which will operate effectively with any extension ladder irrespective of the number of ladder sections of the extension ladder.

An additional object of the present invention is to provide an extension ladder which will reliably prevent any ladder sections from falling freely before their weight is carried by the rope used for raising and lowering the ladder section.

It is also an object of the present invention to provide a simple and efficient hydraulic control for an extension ladder of the above type.

With the above objects in view the present invention includes, in an extension ladder, a first ladder section which extends in a generally upward direction and remains stationary during use of the extension ladder, and a second ladder section which overlaps and is longitudinally movable with respect to the stationary ladder section upwardly to an extended position and downwardly to a collapsed position. A pawl means engages a rung of the movable ladder section to maintain the latter in its extended position, and this pawl means is movable from an engaged position engaging a rung of the movable ladder section to a disengaged position spaced from the rungs of the movable ladder section and located on the same side of the rungs of the movable ladder section as the stationary ladder section. This pawl means of the present in-

2

vention is acted upon by a moving means of the present invention which moves the pawl means in a generally downward direction from its engaged toward its disengaged position so that at this time the pawl means moves in the same general direction that the movable ladder section moves when moving from its extended toward its collapsed position, and therefore with the structure of the invention it becomes unnecessary to raise the movable ladder section before it can be lowered to its collapsed position.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

FIG. 1 is a side elevation illustrating diagrammatically the manner in which the structure of the invention cooperates with a pair of ladder sections;

FIG. 2 shows the structure of FIG. 1 in a position different from FIG. 1;

FIG. 3 shows the structure of FIGS. 1 and 2 in a third position different from the positions of FIGS. 1 and 2;

FIG. 4 is a partly diagrammatic illustration of still another embodiment of the present invention;

FIG. 5 shows the structure of FIG. 4 in a position different from that of FIG. 4; and

FIG. 6 schematically illustrates an extension ladder according to the present invention and the hydraulic control means therefor.

Referring to FIGS. 1-3, a stationary ladder section 1 forms the lower of the pair of ladder sections 1 and 2 shown fragmentarily in FIG. 1. Although the ladder section 1 is referred to as being stationary in this description and in the claims which follow, it is to be understood that the stationary ladder section is stationary in the sense that it remains stationary during use of the extension ladder and forms the lowermost section of the extension ladder. The "stationary" ladder section 1 is capable of being turned from a horizontal position on a fire truck upwardly to a position where the stationary ladder section extends in a generally upward direction during use of the extension ladder. The stationary ladder section 1 carries, in a manner described below in connection with FIG. 6, ropes 3 guided over suitable pulleys carried by the stationary ladder section 1 and connected with pins or the like which are fixed to the movable ladder section 2 so that this movable ladder section is carried by the ropes 3 and is capable of being moved up and down by way of the ropes 3. The movable ladder section 2 overlaps the stationary ladder section 1 and is movable upwardly with respect thereto to an extended position and downwardly with respect thereto to a collapsed position.

The structure of the invention includes a pawl means which in the embodiment of FIGS. 1-3 is formed by the pawl member 4. A moving means cooperates with this pawl means for moving it from the position of FIG. 1 to that of FIG. 3. The pawl means 4 is shown in an engaged position in FIG. 1, and it will be seen that when the pawl means 4 is in its engaged position it engages the underside of a rung 8 of the movable ladder section 2 for preventing downward movement of the movable ladder section. On the other hand, in the disengaged position of the pawl means 4 which is shown in FIG. 3 this pawl means has been displaced out of the plane in which the rungs of the movable ladder section are located toward the plane in which the rungs of the stationary ladder section are located, so that when the pawl means 4 is in the disengaged position shown in FIG. 3 the ropes 3 can be ac-

tuated to lower the movable ladder section to its collapsed position.

In accordance with the present invention the moving means which moves the pawl means 4 moves the latter from its engaged position first in a generally downward direction and then in a direction toward the plane in which the rungs of the stationary ladder section are located. Thus, during the initial movement of the pawl means 4 from its engaged toward its disengaged position the pawl means moves in the same general direction that the movable ladder section moves when moving downwardly from its extended toward its collapsed position, and thus it is unnecessary with the present invention to raise the movable ladder section before it can be lowered to its collapsed position.

The moving means of the invention, according to the embodiment of FIGS. 1-3, includes the lever 5 to one end of which the pawl 4 is pivoted. Actually the free end portion of the lever 5 which carries the pawl 4 is bifurcated to receive a portion of the pawl 4, and as is apparent from FIGS. 1 and 2 which show in a dotted line the innermost part of the bifurcation, the innermost part of the bifurcation limits the turning movement of the pawl 4 in a clockwise direction by the spring 12, so that the pawl 4 cannot move in a clockwise direction, as viewed in FIGS. 1 and 2, beyond the position shown in FIGS. 1 and 2. However, the pawl 4 is free to turn in opposition to the spring 12 in a counter clockwise direction, as viewed in FIGS. 1 and 2.

The moving means which moves the pawl 4 is carried by the stationary ladder section 1 and includes a support means which supports the lever 5 for turning movement at its end portion distant from the pawl 4. This lever 5 is supported for turning movement in a generally downward direction from the position of FIG. 1 to that of FIG. 3 for moving the pawl means 4 from its engaged position shown in FIG. 1 to its disengaged position shown in FIG. 3, and of course the lever 5 is supported by the support means for turning movement in a generally upward direction from the position of FIG. 3 to that of FIG. 1 for placing the pawl means 4 in its engaged position.

The moving means includes in addition to the lever 5 a hydraulic control means which controls the movement of the lever 5, and this hydraulic control means includes a second lever 6 which is turnable between the position shown in FIGS. 1 and 2 and the position shown in FIG. 3. In the position of FIGS. 1 and 2 the lever 6 maintains the lever 5 in its upper position and the pawl 4 in its engaged position, and it will be noted that at this time the lever 6 extends perpendicularly with respect to the lever 5 so that there is no tendency for the lever 6 to turn and it is subject only to pure compression. The hydraulic means includes, in addition to the lever 6 which is supported by the support means carried by the stationary ladder section 1 for turning movement about an axis parallel to the turning axis of the lever 5, a hydraulic cylinder-and-piston means 7. The cylinder of the cylinder-and-piston means 7 is stationary and is supplied at its bottom end through a conduit 13 with a fluid under pressure. The piston of the cylinder-and-piston means 7 is urged by a spring downwardly to the position shown in FIG. 2, so that the spring of the cylinder-and-piston means seeks to maintain the lever 6 in a position extending perpendicularly to the lever 5 and thus the spring of the cylinder-and-piston means tends to locate the parts in the position shown in FIGS. 1 and 2. The hydraulic fluid which enters through the conduit 13 into the cylinder-and-piston means 7 raises the piston thereof in opposition to the spring in the cylinder so as to turn the lever 6 to the position shown in FIG. 3. At this time the piston will have uncovered a return flow conduit 14 so that the piston is shown in FIG. 3 in one of its end positions. During the counter clockwise turning of the lever 6 from the position of FIG. 2 to that of FIG. 3 the lever 5 is turned by its own

weight downwardly from the position of FIG. 2 to that of FIG. 3 so as to place the pawl means 4 in its collapsed position.

After the ladder has been fully collapsed, and it will be noted that in the position of FIG. 3 the pawl 4 does not interfere with the rungs of the movable section 2 so that the latter can be quickly collapsed, the fluid under pressure is no longer supplied through the conduit 13 and the spring acts on the piston of the cylinder-and-piston means 7 for returning the parts 4-6 to the position shown in FIGS. 1 and 2. When it is desired to extend the ladder, the movable section 2 is simply moved upwardly, and it will be noted that the several rungs 8 as they pass the pawl 4 will simply turn the latter in opposition to the spring 12 as each rung 8 engages and moves beyond the pawl 4, as is apparent from FIG. 2. Once the movable ladder section has been moved up to the desired elevation it is simply allowed to descend through whatever distance is required to place the rung 8 which is located directly over the pawl 4 in engagement with the upper end thereof, as indicated in FIG. 1, and the ladder will now remain in its extended position.

In the embodiment of the invention which is illustrated in FIGS. 4 and 5 the pawl means is formed by the elongated pawl member 19 which has a free end adapted to engage a rung 8 of the movable ladder section 2 in the manner illustrated in FIG. 4, when the pawl means is in its engaged position, so as to maintain the movable ladder section in its extended position.

The moving means which moves the pawl means 19 is again carried by the stationary ladder section 1 and also includes a lever. Thus, as is shown in FIG. 4, a lever 18 is provided, and this lever 18 pivotally carries at its right free end portion, as viewed in FIGS. 4 and 5, the pawl means 19. The cylinder of the cylinder-and-piston means 7 is fixedly carried by the stationary ladder section 1, and this cylinder has an integral rigid extension which pivotally carries the lever 18.

In the embodiment of FIGS. 4 and 5 the lever 18 has, in addition to its arm which carries the pawl means 19, a second arm extending beyond the pivotal support for the part of the lever carrying the pawl means 19, and this second arm is pivotally connected to the piston of the cylinder-and-piston means 7. The spring of this cylinder-and-piston means maintains the parts in the position shown in FIG. 4, and in this position the ropes 3 can at any time be acted upon to raise the movable ladder section 2 from its collapsed position and the rungs 8 will successively ride past pawl 19, and a selected rung 8 can then be placed in engagement with the pawl in the manner shown in FIG. 4.

It will be noted that the pawl 19 is fixed with an elongated member 20 which forms a bell crank with the pawl 19, and a supporting structure for the cylinder-and-piston means 7 carries a stationary member 21 which forms a stop to limit the turning of the extension 20 in a clockwise direction, as viewed in FIGS. 4 and 5. A spring is connected at one end to the extension 20 to urge the latter together with the pawl 19 in a clockwise direction, as viewed in FIGS. 4 and 5. Thus, as the rungs 8 move upwardly past pawl 19, the pawl 19 together with the extension 20 will be free to turn in a counter clockwise direction in opposition to the spring and will then immediately return to the position determined by the stop 21 as soon as a rung 8 has moved upwardly beyond the pawl 19.

It will be noted that when a rung 8 is engaged by the pawl 19 in the position shown in FIG. 4, the movable ladder section will exert a downward force on the pawl 19 tending to turn the latter in a clockwise direction, and of course such turning is prevented by the stop member 21. At this time, as is apparent from FIG. 4, the pawl 19 extends in exactly the same direction as and forms for practical purposes a straight extension of the lever 18 so

that when the parts are in the position shown in FIG. 4 there is virtually no stress on the piston of the cylinder-and-piston means 7. Of course, when it is desired to move the pawl means 19 to its disengaged position shown in FIG. 5 fluid under pressure is introduced through the conduit 13 into the cylinder of the cylinder-and-piston means 7 so as to advance the piston toward the conduit 14 and eventually the piston will reach the position shown in FIG. 5, the piston at this time moving in opposition to the spring within the cylinder of the cylinder-and-piston means 7. During the initial clockwise turning of the lever 18, as viewed in FIG. 4, the end of the pawl 19 pivotally connected to the lever 18 will move downwardly, and of course at this time the extension 20 will slide along the stop member 21, the result being that during the initial portion of the turning of the lever 18 from the position of FIG. 4 to that of FIG. 5 the pawl 19 moves downwardly while remaining in engagement with the rung 8 so that the ropes 3 which may be slack when the parts have the position shown in FIG. 4 will be tensioned and will take up the weight of the ladder section 2. After the initial portion of the movement of the lever 18, which may constitute approximately the first half of its total stroke, for example, the continued turning of the lever 18 together with the maintenance of the extension 20 against the stop 21 will result in turning of the pawl 19 away from the plane in which the rungs of the ladder section 2 are located toward the plane in which the rungs of the stationary ladder section 1 are located. Of course, as soon as the pawl 19 is out of the plane in which the rungs 8 are located the ladder section 2 can be lowered to its collapsed position.

With the embodiment of FIGS. 1-3 as well as with the embodiment of FIGS. 4 and 5 the lever which is connected to the pawl means turns so as to move the pawl means first in a generally downward direction in advance of the downward movement of the ladder section 2 so that the ropes 3 will be fully tensioned by the weight of the ladder section 2 before the pawl means leaves the movable ladder section, and thus, free falling of the movable ladder section with sudden yanking of the ropes 3 is reliably avoided.

FIG. 6 illustrates diagrammatically the hydraulic installation as well as the several sections of a ladder and the cable system for actuating the sections. Thus, it will be seen from FIG. 6 that the stationary ladder section 1 forms the lowest of the ladder sections while the movable ladder section 2 is the next highest ladder section, and a pair of additional successive ladder sections are shown in FIG. 6. The ropes 3 which support the movable ladder section 2 are guided over pulleys carried by upper portions of the stationary ladder section 1, and these ropes 3 are connected with a winch 25 which can be turned in one direction or the other so as to take up or let out the ropes 3 and thus raise or lower the movable ladder section 2.

As may be seen from FIG. 6, a pair of additional ropes are respectively fixed to the top ends of the side members of the stationary ladder section 1, are guided over pulleys carried by upper side portions of the ladder section 2, and are connected with lower side portions of the third ladder section. As a result when the movable ladder section 2 moves upwardly, the pulleys carried thereby also move upwardly and act on the ropes guided over these pulleys to raise the third ladder section simultaneously with the raising of the second ladder section 2, and of course the third ladder section will by its own weight descend when the ladder section 2 descends.

In much the same way a third set of ropes 3 are fixed to the top ends of the ladder section 2, are guided over pulleys carried by the third ladder section and are connected to bottom end portions of the fourth ladder section, so that as the third ladder section moves up and down the pulleys carried thereby will also move up and down to act on the third set of cables for raising and

lowering the fourth ladder section, and thus it is apparent that operation of the winch 25 will result in raising and lowering of the entire extension ladder irrespective of the number of sections included in the extension ladder. Furthermore it is apparent that the single pawl means carried by the moving means supported by the stationary ladder section 1 and cooperating with a single rung of the movable ladder section 2 will act to maintain the entire extension ladder extended to the degree selected by the operator.

As is apparent from FIG. 6, there are actually a pair of pawls cooperating with the selected rung of the movable ladder section, and FIG. 6 shows the pair of levers 6 of the embodiment of FIGS. 1-3. The pair of levers 6 are supported by a common pivot pin in the form of an elongated rod, and in the same way the pair of levers 5 which cooperate with the pair of levers 6 may also be supported by a common rod passing therethrough. The pair of pawls 4 which form the pawl means may be interconnected by a rod which will guarantee that they turn as a unit. In the same way a pair of pawls 19 and extensions 20 as well as a pair of levers 18 are provided for the embodiment of FIGS. 4 and 5. However, only one cylinder-and-piston means is provided, as indicated in FIG. 6.

The winch 25 is driven by an oil motor 26 which acts through the reduction gearing assembly 27 on the winch 25. Oil under pressure is delivered to the motor 26 to actuate the latter from a pump 28 which derives the oil from a reservoir 29. The oil after passing through the motor 26 returns by way of a conduit 30 back to the tank 29. The flow of oil is controlled by a manually operable valve means 32 which is illustrated in FIG. 6 in its neutral position. The diagrammatically illustrated valve means 32 has a handle 35 accessible to the operator for manipulating the valve. When the handle 35 is turned in a clockwise direction, as viewed in FIG. 6, from the illustrated neutral position the ladder will be collapsed, while when the handle 35 is turned in a counter clockwise direction, as viewed in FIG. 6, from the illustrated neutral position the ladder will be extended. The turnable valve member of the valve means 32 includes a bore 33 passing diametrically therethrough, a relatively small bore 41 extending perpendicularly from the bore 33, an arcuate groove 37, and a substantially sickle-shaped groove 38 communicating with the end of the bore 41 distant from the bore 33. The discharge conduit 36 for the fluid under pressure delivered by the pump 28 leads from the pump 28 to the valve means 32, and upstream of the valve means 32 is a safety valve which provides communication between the conduits 30 and 36 in the event that the pressure in the conduit 36 becomes too high. The pressure conduit 13 leads from the cylinder-and-piston means 7 to the valve 32, while the conduit 14 communicates directly with the return flow conduit 30. A conduit 34 provides communication between the valve 32 and the return flow conduit 30, and a conduit 40 leads from the valve 32 to the motor 26. It will be noted that the conduits 13, 36, 40 and 34 respectively communicate with the valve 32 at points angularly spaced by 90° with respect to each other.

Assuming that the ladder is collapsed and that it is desired to extend the ladder, the operator will simply turn the handle 35 in a counter clockwise direction through a relatively small angle sufficient to place conduits 36 and 40 in communication with each other through the groove 38. At this time the opposite ends of the bore 33 will be closed, and the conduits 13 and 34 will be placed in communication with each other so that the conduit 13 at this time is at low pressure and thus the spring of the cylinder-and-piston means will have no difficulty in maintaining the pawl means 4 or 19 in its engaged position. The handle 35 is held in the position where the conduits 36 and 40 communicate through the groove 38 until the desired degree of extension of the

ladder is obtained, and then the handle 35 is returned by the operator to the neutral position shown in FIG. 6. At this time the groove 37 does not communicate with the conduit 34 so that the conduit 13 is closed, and thus the piston of the cylinder-and-piston means 7 is very reliably held in its lowermost position shown in FIGS. 1 and 4 because the force required to raise the piston would have to be sufficient to produce a vacuum in the hollow interior of conduit 13 and groove 37 which is filled with oil. Thus, the pawl means is very reliably held in its extended position and the rung of the ladder section 2 which engages the pawl means is very reliably supported. It may be that when the operator returns the valve 32 to its neutral position the selected rung of the ladder section 2 is spaced above the pawl means. As is apparent from FIG. 6 when the valve 32 is in its neutral position the bore 33 provides communication between the conduits 36 and 34 so that the fluid under pressure simply circulates back to the reservoir 29. Also, in the neutral position of the valve 32 the pressure conduit 40 of the motor 26 communicates through the groove 38 and the bore 41 of relatively small diameter with the bore 33 and conduit 34. As a result the weight of the movable ladder sections will cause them to move downwardly turning the winch 25 and the gearing 27 as well as the motor 26 through which the fluid can now flow in the reverse direction through the conduit 40 and slowly through the bore 41 back along the conduits 34 and 30 to the reservoir, so that in this way irrespective of the height of the selected rung of the ladder section 2 above the pawl means when the operator returns the lever 35 to its neutral position, the ladder will automatically move down until the selected rung rests on and is supported by the pawl means.

When it is desired to collapse the extended ladder, the operator turns the handle 35 in a clockwise direction through an angle as sufficient to place conduits 13 and 36 in communication with each other through the groove 37 and conduits 34 and 40 in communication with each other through the groove 38. In this way the motor 26 will easily turn in the direction reverse to the winding direction since the conduit 40 communicates with the return flow conduit without the resistance to the flow provided by the conduit 41 of small diameter. Thus, the movable ladder sections will be able to descend fairly rapidly under their own weight, the resistance provided by the flow of the hydraulic fluid through the conduit 40 and the conduit 34 preventing free falling of the ladder sections. Of course, the downward movement of the ladder sections will not start until the piston is displaced in the cylinder of the cylinder-and-piston means 7 and the fluid under pressure flowing through the conduit 13 displaces the piston so as to initiate the collapse of the ladder in the manner described above. Once the pawl means has moved out of the plane of the rungs 8, the ladder sections move downwardly and the motor 26 simply turns in a reverse direction, the fluid at this time simply circulating around through the motor through the short-circuit provided by the communication between the conduits 40 and 34. Of course, when the piston has been displaced beyond the conduit 14 the fluid under pressure will return through the conduit 14 to the tank 29. Once the conduit 14 receives fluid from the conduit 13, part of the fluid from the conduit 14 may flow to the motor 26 to replace fluid displaced therefrom into the conduit 40, and the ladder sections will descend in the manner described above. As soon as the ladder is totally collapsed the operator returns the valve 32 to its neutral position.

The provision of a pair of ropes 3 for each of the movable ladder sections located beyond the ladder section 2 provides the desired safety since if any one rope should fail the other rope will still hold the ladder section.

Also, the pawl means may of course be made up

7
8
of a single pawl member rather than a pair of interconnected pawl members.

It will be understood that each of the elements described above, or two or more together, may also find a useful application in other types of ladders differing from the types described above.

While the invention has been illustrated and described as embodied in extension ladders, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic and specific aspects of this invention and, therefore, such adaptations should and are intended to be comprehended within the meaning and range of equivalence of the following claims.

What is claimed as new and desired to be secured by Letters Patent is:

1. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means pivotable about a pivot axis therethrough and having an engaged position engaging a rung of said movable ladder section for preventing downward movement thereof and a disengaged position spaced from and located on the same side of the rungs of said movable ladder section as said stationary ladder section, said pivot axis in said disengaged position of said pawl means being located downwardly from its location in the engaged position of said pawl means; a lever pivotally connected to said pawl means at said pivot axis; support means carried by said stationary ladder section and supporting said lever for turning movement in a downward direction for moving said pawl means from said engaged position to said disengaged position and in an upward direction for moving said pawl means from said disengaged to said engaged position thereof; and means cooperating with said lever for controlling the turning movement thereof.

2. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means pivotable about a pivot axis therethrough and having an engaged position engaging a rung of said movable ladder section for preventing downward movement thereof and a disengaged position spaced from and located on the same side of the rungs of said movable ladder section as said stationary ladder section, said pivot axis in said disengaged position of said pawl means being located downwardly from its location in the engaged position of said pawl means; a lever pivotally connected to said pawl means at said pivot axis; support means carried by said stationary ladder section and supporting said lever for turning movement in a downward direction for moving said pawl means from said engaged position to said disengaged position and in an upward direction for moving said pawl means from said disengaged to said engaged position thereof; and hydraulic means cooperating with said lever for controlling the turning movement thereof, said hydraulic means controlling said lever so that the latter will move downwardly in advance of the downward movement of said movable ladder section toward said collapsed position thereof.

3. In an extension ladder, in combination, a first ladder

section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means pivotable about a pivot axis therethrough and having an engaged position engaging a rung of said movable ladder section for preventing downward movement thereof and a disengaged position spaced from and located on the same side of the rungs of said movable ladder section as said stationary ladder section, said pivot axis in said disengaged position of said pawl means being located downwardly from its location in the engaged position of said pawl means; a lever pivotally connected to said pawl means at said pivot axis; support means carried by said stationary ladder section and supporting said lever for turning movement in a downward direction for moving said pawl means from said engaged position to said disengaged position and in an upward direction for moving said pawl means from said disengaged to said engaged position thereof; and hydraulic means cooperating with said lever for controlling the turning movement thereof, said lever during its downward turning movement moving said pawl means first in a generally downward direction and then away from the plane in which the rungs of said movable ladder section are located toward the plane in which the rungs of said stationary ladder section are located.

4. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means having an engaged position engaging a rung of said movable ladder section for preventing downward movement thereof and a disengaged position spaced from and located on the same side of the rungs of said movable ladder section as said stationary ladder section; a lever pivotally carrying said pawl means at one end portion of said lever; support means carried by said stationary ladder section and supporting said lever at an opposite end portion thereof for turning movement in a generally downward and generally upward direction, said lever when turning in said generally downward direction moving said pawl means toward said disengaged position thereof to release said movable ladder section for movement to said collapsed position thereof without first requiring raising of said movable ladder section; a second lever turnably carried by said support means and extending substantially perpendicularly with respect to and engaging said first-mentioned lever at an underside thereof for preventing downward movement of said first-mentioned lever when said pawl means is in said engaged position thereof; and hydraulic means operatively connected with said second lever for turning the latter to a position where said second lever extends at an acute angle with respect to said first-mentioned lever and releases the latter for downward movement so as to move said pawl means from said engaged toward said disengaged position thereof.

5. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means having an engaged position engaging a rung of said movable ladder section for preventing downward movement thereof and a disengaged position spaced from and located on the same side of the rungs of said movable ladder section as said stationary

ladder section; a lever pivotally carrying said pawl means at one end portion of said lever; support means carried by said stationary ladder section and supporting said lever at an opposite end portion thereof for turning movement in a generally downward and generally upward direction, said lever when turning in said generally downward direction moving said pawl means toward said disengaged position thereof to release said movable ladder section for movement to said collapsed position thereof without first requiring raising of said movable ladder section; a second lever turnably carried by said support means and extending substantially perpendicularly with respect to and engaging said first-mentioned lever at an underside thereof for preventing downward movement of said first-mentioned lever when said pawl means is in said engaged position thereof; and hydraulic means operatively connected with said second lever for turning the latter to a position where said second lever extends at an acute angle with respect to said first-mentioned lever and releases the latter for downward movement so as to move said pawl means from said engaged toward said disengaged position thereof.

6. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means pivotable about a pivot axis therethrough and having an engaged position engaging a rung of said movable ladder section for preventing downward movement thereof and a disengaged position spaced from and located on the same side of the rungs of said movable ladder section as said stationary ladder section, said pivot axis in said disengaged position of said pawl means being located downwardly from its location in the engaged position of said pawl means; a lever pivotally connected to said pawl means at one end portion of said lever and at said pivot axis; support means carried by said stationary ladder section and supporting said lever for turning movement in generally upward and downward directions for moving said pawl means between said engaged and disengaged positions thereof, respectively, said pawl means including an elongated member which engages a rung of said movable ladder section when said pawl means is in said engaged position thereof and said elongated member extending in the same direction as and forming substantially an extension of said lever when said pawl means is in said engaged position thereof; and means cooperating with said lever for controlling the turning movement thereof.

7. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means pivotable about an axis therethrough and having an engaged position engaging a rung of said movable ladder section for preventing downward movement thereof and a disengaged position spaced from and located on the same side of the rungs of said movable ladder section as said stationary ladder section, said pivot axis in said disengaged position of said pawl means being located downwardly from its location in the engaged position of said pawl means; a lever pivotally connected to said pawl means at one end portion of said lever and at said pivot axis; support means carried by said stationary ladder section and supporting said lever for turning movement in generally upward and

downward directions for moving said pawl means between said engaged and disengaged positions thereof, respectively, said pawl means including an elongated member which engages a rung of said movable ladder section when said pawl means is in said engaged position thereof and said elongated member extending in the same direction as and forming substantially an extension of said lever when said pawl means is in said engaged position thereof, said lever having an extension extending beyond the turning axis provided by said support means and forming an arm of said lever; and hydraulic means operatively connected with said arm for turning said lever so as to move said pawl means between said positions thereof.

8. In an extension ladder, in combination, a first ladder section adapted to remain stationary while extending in a generally upward direction during use of the extension ladder; a second ladder section overlapping said first ladder section and movable longitudinally with respect thereto in a generally upward direction to an extended position and in a generally downward direction to a collapsed position; pawl means pivotable about a pivot axis therethrough and having an engaged position engaging a rung of said movable ladder section for preventing downward movement thereof and a disengaged position spaced from and located on the same side of the rungs of said movable ladder section as said stationary ladder section, said pivot axis in said disengaged position of said pawl means being located downwardly from its location in the engaged position of said pawl means; a lever pivotally connected to said pawl means at one end portion of said lever and at said pivot axis; support means carried by said stationary ladder section and supporting said lever for turning movement in generally upward and downward directions for moving said pawl means between 35

said engaged and disengaged positions thereof, respectively, said pawl means including an elongated member which engages a rung of said movable ladder section when said pawl means is in said engaged position thereof 5 and said elongated member extending in the same direction as and forming substantially an extension of said lever when said pawl means is in said engaged position thereof, said pawl means including a second elongated member fixed to and extending angularly from said first-mentioned elongated member and said stationary ladder section carrying a stop member in the path of movement of said second elongated member during downward turning of said lever while said pawl means moves from said engaged toward said disengaged position for engaging said second elongated member and turning said pawl means with respect to said lever while the latter continues its downward movement for displacing said pawl means out of the plane in which the rungs of said movable ladder section are located toward the plane in 20 which the rungs of said stationary ladder section are located; and means cooperating with said lever for controlling the turning movement thereof.
